UNITED STATES PATENT OFFICE.

CHARLES D. HERROLD, OF SAN JOSE, CALIFORNIA.

OSCILLATOR FOR WIRELESS TRANSMISSION.

1,096,717.

Specification of Letters Patent. Patented May 12, 1914.

Application filed April 21, 1913. Serial No. 762,533.

To all whom it may concern:

Be it known that I, CHARLES D. HERROLD, chief engineer of National Wireless Tel. & Tel. Co., a citizen of the United States, residing at San Jose, in the county of Santa Clara and State of California, have invented new and useful Improvements in Oscillators for Wireless Transmission, of which the following is a specification.

10 This invention relates to an apparatus for the production of oscillating currents of high frequency.

The object of the invention is to provide a simple, practical apparatus for the production 15 of oscillating currents of high frequency, persistency, force and effect, by means of which wireless telephony and telegraphy may be carried out.

Another object of the invention is to improve 20 the construction of the electrodes, so as to produce a steady, uniform oscillating spark, and which will also allow a perfect circulation of the imperfect cooling liquid, thus, producing uniform transmission of 25 high efficiency.

Further objects will appear hereinafter.

The invention consists of the parts and the construction and combination of parts as hereinafter more fully described and claimed, 30 having reference to the accompanying drawings, in which—

Figure 1 is a longitudinal section showing the construction of the oscillator. Fig. 2 is a section on the line X—X of Fig. 1.

35 In most forms of oscillators heretofore constructed it has been found that there are times when the oscillating spark causes explosive effects between the electrodes in the oscillating chamber. This is generally produced by a sudden rise in the voltage of the current passing through the electrodes. A sudden increase of voltage generally causes an excessive generation of vapors or gases at the point of discharge, which causes the 40 explosive effect previously mentioned. The oscillating spark is thus caused to waver for an instant, causing an unsteadiness of voice. In apparatus employing more than three sets of electrodes or oscillators the above-mentioned irregularities are more noticeable, because the wavering of the oscillating spark caused by the explosive effect will be multiplied with each additional oscillating member.

45 The main object of this invention is to

produce a novel form of electrode in which the above-mentioned explosive defects or irregularities of oscillation may be practically eliminated.

Referring to the drawings: The invention 50 consists of an oscillatory spark gap apparatus having spaced terminal tubular electrodes 2 and 3, which may be constructed of metal and carbon, or either; the faces of which are opposed to each other and parallel. 55 In this instance I have shown the electrodes as being mounted within a vertically disposed cylinder 4, having a bottom 5, and a base flange 6. The outside of the cylinder is provided with a water jacket 7, connected 60 with a suitable circulating system not here shown. The cylinder is also provided with a perforated cover 8 in which is placed an insulating bushing 9, lined with a metal bushing 9^a, through which passes a rod 10, carrying a metal cap 11, provided with elastic fingers or holders 12 in which is supported the tubular carbon electrode 2. The lower metal electrode 3 may consist of any suitable metal composition, such as brass or copper, 65 and is also tubular in construction, being suitably supported as here shown by a downwardly extending arm 13, suitably secured and insulated in the cover 8. The upper end of the arm 13 is provided with the 70 usual form of connection 14 to which one end of the electrical circuit is connected, while the downwardly extending portion of the arm 13 carrying the tubular electrode 3 is covered with any suitable moisture-proof 75 insulating material 15 to prevent any short-circuiting of the current within the oscillating chamber or cylinder 4.

In oscillating apparatus of this construction it has been proven in actual practice 80 that at least one of the electrodes shall be of metal, as these conserve their shape to a higher degree than the carbon electrodes which is of great importance for the stability and uniformity of the spark. Likewise 85 it is advantageous to use electrodes of metal as they are better heat conductors, and will usually quickly lead off the heat from the spark. One metal electrode has also been found advantageous because of the valve action 90 due to the difference of potential created by polarization at the metallic surface. When carbon and copper are employed, the positive terminal of the source of supply is 95 connected to the copper electrode. When 100

105 110

carbon and aluminum are used the negative terminal of the source of supply is connected to the aluminum electrode.

The oscillating chamber or cylinder 4 is filled with an imperfectly conducting liquid for the purpose of entirely submerging the electrodes. The oscillating spark in jumping from one electrode to another will allow the liquid to heat at that point. The imperfectly conducting liquid has the peculiar nature when heated of producing greater resistance than when cool, thus causing the next discharge or oscillation of the current between the electrodes to seek a point of least resistance, which will naturally be at the coolest point between the electrodes, thereby causing the oscillating spark to instantly shift or change its position. The heating of the imperfectly conducting liquid will thus cause the spark to travel around the tubular rim of the opposed electrodes, thus preventing any pitting or excessive burning of the carbon electrode at any one point. The carbon electrode is thus evenly wasted or burned, and the frequency of oscillation as well as the volume of electrical energy is persistent and uniform.

The walls of the tubular electrodes here shown are very thin, thus preventing the spark from shifting from the inner to the outer edge of the tube, which might have a tendency to cause variation in oscillation. However, by thinning down the walls of the electrodes to form the tubes here shown, it can easily be seen that the oscillating spark is forced into a restricted path which compels it to move smoothly in a uniform path around the edge of the electrodes.

Another point of advantage gained by the tubular construction of the electrodes here shown is that it eliminates the necessity of water-cooling the electrodes; the imperfectly conducting liquid proving sufficient in this instance to cool the electrodes. As a free circulation is produced.

By referring to the sectional view in Fig. 1 it can be seen that the imperfectly conducting liquid will constantly pass through the center portion of the electrodes in the direction of arrows *a* as the liquid becomes heated, thus causing a constant free circulation of the liquid which is sufficient to carry off any excessive heat generated by the electrodes, the liquid being in turn cooled by the circulating water contained in the jacket 7. The carbon electrode 2 may be adjusted with relation to the stationary electrode 3 in any suitable manner. This may be produced by lifting the carbon supporting rod 10 in the direction of the arrow *b*, which may be accomplished by providing a suitable clutching mechanism indicated at 16, which in turn is actuated by a centrally pivoted rocking lever 17, the outer end of which is connected to the movable core 18

of a solenoid magnet 19; the lifting movement of the lever 17, clutch 16, and carbon supporting rod 10, being adjusted by a set screw 20. The solenoid magnet 19 may be connected on the main oscillating circuit passing through the electrodes 2 and 3, thus causing the electrodes to be separated the moment the circuit is closed.

The apparatus here shown is neat in appearance, prompt and reliable in its action, and takes no more space than the usual form of apparatus heretofore employed. The novel construction of the electrodes here shown, which forms the subject matter of this invention, eliminates any water cooling connections for the purpose of cooling the electrodes, and also produces a spark gap which is evenly burned or wasted; and between which explosive effects, such as previously mentioned, are practically eliminated, as the gases generated may be quickly discharged in any direction without resistance, thus preventing any irregularity or wavering of the oscillations.

The materials and finish of the several parts of the apparatus are such as experience and judgment of the manufacturer may dictate.

Having thus described my invention, what I claim and desire to secure by Letters Patent is:

1. An oscillatory circuit spark gap apparatus consisting of opposed interspaced terminal electrodes, submerged in an imperfectly conducting liquid, said electrodes having parallel separated opposed narrow restricting surfaces between which the lines of discharge travel.

2. An oscillatory circuit spark gap apparatus consisting of opposed interspaced tubular terminal electrodes, said electrodes having parallel separated opposed annular rim surfaces between which the lines of discharge may continually change, a container within which the electrodes are mounted, and an imperfectly conducting liquid in the container in which the electrodes are submerged.

3. An oscillatory circuit spark gap apparatus consisting of opposed interspaced tubular terminal electrodes, said electrodes having parallel separated opposed annular rim surfaces between which the lines of discharge may continually change, a container within which the electrodes are mounted, an imperfectly conducting liquid in the container in which the electrodes are submerged, and means whereby said medium may be circulated with relation to the exterior and interior of the electrodes.

4. An oscillatory circuit spark gap apparatus consisting of opposed interspaced tubular terminal electrodes, said electrodes having parallel separated opposed annular rim surfaces between which the lines of dis-

- charge may continually change, a container within which the electrodes are mounted, an imperfectly conducting liquid in the container in which the electrodes are submerged, 5 means whereby said medium may be caused to constantly circulate through the interior of the electrodes by entering through the lower end of the lower electrode and discharging through the upper end of the upper electrode and returned again by passing around the exterior surface of the electrodes, and means for cooling said medium.
5. An oscillatory circuit spark gap apparatus consisting of opposed interspaced 15 tubular terminal electrodes, said electrodes having parallel separated opposed annular rim surfaces between which the lines of discharge may continually change, a container, an imperfectly conducting liquid in said chamber in which the electrodes are submerged, a cover inclosing said chamber, a rod insulated from the cover adjustably mounted in the cover and extending within the container, spring clip arms secured on the outer end of the rod in which the upper tubular electrode is secured, a stationary 45 arm insulated from the cover secured to the cover extending down into the container, to which the lower tubular electrode is secured, and means for circulating the imperfectly conducting liquid through and around 50 the tubular electrodes.
- In testimony whereof I have hereunto set my hand in the presence of two subscribing witnesses.
